RELAY

Oscar S. Field, Rochester, N. Y.; assignor to General Railway Signal Company, Rochester, N. Y.

Application April 5, 1930, Serial No. 442,022

15 Claims. (Cl. 175—320)

This invention relates in general to relays, and has more particular reference to a time element of relay of general use and particularly adapted for railway use.

5 In many instances it is desirable to have a relay which does not immediately respond to an operation but which responds and picks up, for example, only after a predetermined interval of time has elapsed from said operation.

10 In other cases it is desirable to have a relay which picks up immediately on an operation (as the throwing of a control switch) and then automatically releases only after a predetermined lapse of time from the pick-up. Such relays find use in many situations such, for example, as in the well known A. P. B. system of signaling in automatic train control systems of various types, and the like.

15 With the above and other objects in mind, it is proposed in accordance with the present invention to provide mechanical means for controlling a relay so as to insure the desired lapse of time between control operation and relay operation, whereby to provide a relay which is slow to pick up or slow to release, without modifying the electrical characteristics of the relay in question, as for example is very generally done in making a slow release relay by providing the winding of the relay with a short-circuited cop-

20 per band or the like.

More specifically, it is proposed, in accordance with the present invention, to provide a relay having an energizing circuit including two contacts in series. One of the contacts is biased to a position to open the circuit while the other contact is normally in open circuit position and is provided with a holding winding whereby, once placed in circuit closing position, it will remain in such position so long as the holding winding is energized. The two contacts are arranged to be operated by the plunger of a solenoid, in sequence, in one direction, with a timing element such as a clock work connected to be wound up by the movement of the solenoid plunger. On release of the solenoid plunger when its winding automatically becomes de-energized, the rate of return movement of the plunger is determined by the timing element, and it is only after this plunger has returned, under control of the timing element, to its original position, that the desired operation of the relay takes place.

25 Further objects, purposes and characteristic features of the present invention will appear as the description progresses, reference being made

to the accompanying drawings, showing, solely by way of example, and in no manner whatsoever, in a limiting sense, two forms which the invention can assume. In the drawings:

Fig. 1 is a schematic view, wholly divorced from actual structure, of one form of the invention.

Fig. 2 is a schematic view of a modified form of the invention.

Fig. 3 is a sectional elevation of one commercial form of the invention.

Fig. 4 is a sectional plan view, taken on line 4—4 of Fig. 3, viewed in the direction of the arrows.

In describing the invention it is thought clear to first describe it in connection with the schematic views of Figs. 1 and 2, and then to briefly describe the same in connection with the commercial form which the invention can assume, as shown in Figs. 3 and 4.

Referring now to Fig. 1, there is here shown a relay R which it is desired to so control as to make it slow to pick up. For controlling this relay R, there is employed a solenoid-operated plunger P, having a setting winding SW, which, when energized, raises plunger P. Plunger P is connected to its lower end an arm 1 which is fixed to a shaft 2 of a timing element TE which can be of any usual or desired form, as a clock work, such as shown for example in the C. S. Bushnell Patent Ser. No. 1,725,729 granted August 20, 1929. The arm 1 has one end in the form of a pointer 3 which can pass over a graduated scale on the casing of the timing element TE, if desired. The other end of arm 1 is arranged to bear against a toe 4 of a contact 5, pivoted at 6 and biased by gravity to move in a clockwise direction, but restrained against such movement and held in its upper position, as shown, by the arm 1, when plunger P is in its lower position, as shown.

A second contact 7, of the make-before-break type, is arranged to be moved from its lower position, as shown, to an upper position, when plunger P is raised, after an predetermined amount of lost motion has been taken up between the contact 7 and an adjustable nut 8 having a lock nut 9, therefor, adjustable on a threaded portion 10 on plunger P. A holding stick winding HC is provided for contact 7 and operates to hold contact 7 in its upper position when energized.

The operation of the parts shown in Fig. 1 is as follows. In the positions of parts as shown in Fig. 1, with switch S open, the winding SW

is de-energized, stick winding HC is de-energized, relay R is de-energized, plunger P is in its lower position and the timing element TE is unwound or run down. The switch S can be 5 a hand operated switch or it can be automatically controlled by means of train movement or in any other desired manner.

On closure of switch S, the setting winding SW of the solenoid is energized through a circuit including battery B, switch S, wires 11 and 12, winding SW, wire 13, contact finger 7 and back point and wire 15.

On energization of winding SW, plunger P is 15 raised to thereby rotate arm 1 in a counter-clockwise direction to release toe 4 of contact 5 and allow it to open under the force of gravity. Rotation of arm 1 also winds up the timing element TE, and, as soon as the nut 8 on plunger P contacts with contact finger 7, this contact is 20 moved to its upper position in which position it is held by the stick winding HC which is energized through the stick circuit including battery B, switch S, wires 11 and 38, winding HC, wire 14, finger 7 and front point of HC, and wire 15.

25 Before closure of switch S, the energizing circuit for relay R which includes contact finger 5 and front point, and contact finger 7 and front point was open at contact finger 7 to thereby maintain relay R de-energized.

30 After plunger P has moved to its upper position, as described just above, contact finger 7 is positioned in its upper position to close the energizing circuit for relay R at this point, but prior to this closing of the circuit, the circuit 35 was opened by the dropping of contact finger 5. As a result relay R, which was de-energized when switch S was first closed, remains de-energized after plunger P has been moved to its upper position.

40 Movement of plunger P to its upper position breaks the energizing circuit for winding SW at contact finger 7 and back point to thereby allow the plunger to move downwardly under the force of gravity at a rate determined by the 45 timing element TE. It is only after the plunger P has reached its lowermost position that it closes contact finger 5 and front point to thereby complete the energizing circuit for relay R which includes battery B, wire 15, contact finger 7 and 50 front point, wire 35, relay R, wire 16, contact finger 5 and front point, wires 37, 38 and 11, and switch S in closed position.

When switch S is opened, the holding coil HC is de-energized to allow contact finger 7 to 55 drop to its lower position to thereby restore all parts to their normal shown positions.

It will be readily appreciated from the above 60 description, that the time elapsed between closure of switch S and the picking up of relay R, is determined by the extent to which the timing element TE has been wound up during the upward movement of the plunger P. Furthermore the amount of upward movement of plunger P can be readily adjusted by the adjustment of the nut 8 on plunger P to thereby adjust the wind up of TE and hence the timing of the pick-up of relay R.

Referring now to Fig. 2, there is here shown a 70 slightly modified form wherein the controlled relay R¹ is connected up to a back point of contact finger 5¹, instead of to a front point as in Fig. 1. This results in relay R¹ being slow to release instead of slow to pick up, as described above in connection with Fig. 1.

75 In the form shown in Fig. 2, on closing switch

S, contact finger 5¹ drops and contact finger 7 is moved to its upper position thereby immediately completing the energizing circuit for relay R¹ so that this relay picks up practically simultaneously with the closure of switch S.

80

Relay R¹ however releases only after a lapse of time which is determined by the time required for plunger P to move from its upper position to its lower position, as it is only after the plunger P has reached its lower position that the energizing circuit for relay R¹ is broken at contact finger 5¹.

85

It is thus seen from Figs. 1 and 2 that means have been provided for making a relay either slow to pick up or slow to release, together with adjusting means for varying the time lag as desired, the slow acting relay not having any different electrical characteristics, per se, from those of quick acting relays.

90

Referring now to Figs. 3 and 4, there is here shown a physical embodiment, in a commercial form, of the invention schematically shown in Figs. 1 and 2.

95

The device in a commercial form, includes a casing 17 and a cover 18 of insulated material, 100 with a solenoid element 19 of the shell type positioned in the casing and held in place by a flange 20 resting on a collar 21 of the cover 18.

Carried by the core of the solenoid is the setting winding SW, and the holding coil HC, together with the plunger P.

105

The plunger P has the arm 1 connected to its lower end as by a cotter pin 11¹, with the arm 1 carried on the shaft 2 of the timing element TE, and with the other end of the arm 1 in the form 110 of a pointer 3. The timing element TE is shown as mounted on supporting pins 22 having springs 23 sleeved thereon for resiliently supporting the element.

110

On the plunger P is an operating nut 8 which 115 can be adjusted on the threaded portion 10 of the plunger and then clamped in adjusted position by the lock nut 9, the plunger P passing through an enlarged opening 7¹ of the armature 7², whereby to permit lost motion travel of 120 the plunger with respect to armature 7² until the operating nut 8 comes into contact with an arm 24 on the armature, after which further movement of the plunger P moves the armature 7² to its upper position to be there held by the 125 holding coil HC.

115

The gravity biased contact 5 is shown as pivoted at 6 to a support bracket 6¹ supported by the core member 19 at 25. The contact finger 7 is shown as operating between front and back 130 fixed contacts 26 and 27, the contact 27 being carried by the bracket 6¹, and insulated therefrom by an insulator 36.

120

In the commercial form shown in Figs. 3 and 4, the contact finger 5 is equipped with both 135 a front and a back fixed contact 28 and 29 respectively, whereby to permit the relay R to be connected either as shown in Fig. 1, for slow pick-up, or as shown in Fig. 2, for slow release; or two relays can be connected at the same time, 140 one to be slow to pick-up and the other slow to release.

130

For facilitating an understanding of the structure of Figs. 3 and 4, the connection thereto of the relay R and of the battery B, and the 145 initiating switch S, has been shown in dotted lines. As appears from the drawings, it is merely necessary to connect the battery, as B, across the binding posts 30 and 31 together with the control switch S, and to connect relay R across 150

140

150

binding posts 32 and 33, if it is to be a slow pick-up relay. If R is to be a slow release relay, it is connected between binding post 32 and a post (not shown in the drawing) connected to the back fixed contact 29.

It is clear from the above description that the present invention has provided means for making any usual, normally fast acting relay either slow to release or slow to pick up, and adjustable

10 as to timing within the limits of the structure employed; and all without modifying the relay in any manner, but simply by connecting it up properly to the timing mechanism of this invention.

15 The above rather specific description of two forms of the present invention are given solely by way of example, and are not intended, in any manner whatsoever, in a limiting sense. Obviously, the invention can assume many different physical forms, and is susceptible of numerous modifications, and all such forms and modifications are intended to be included in this application, as come within the scope of the appended claims.

25 Having described my invention, I now claim:—

1. In combination, a circuit including an electrically operated time controlled contact, and an electrically operated contact, a solenoid for sequentially operating said contacts upon energization of the solenoid, means for automatically de-energizing said solenoid, and means for preventing the sequential return of said contacts on de-energization of said solenoid whereby to

30 produce a predetermined time controlled operation of said circuit.

2. In combination, a normally open energizing circuit for a relay, having an electrically operated, time controlled, contact, and an electrically operated contact, a solenoid for sequentially operating said contacts without closing said circuit, upon energization of the solenoid, means for automatically de-energizing said solenoid, and means for preventing the sequential return 40 of said contacts on de-energization of said solenoid whereby to close said circuit a predetermined time after energization of said solenoid.

3. In a slow acting device, in combination, a timing element, a solenoid, a solenoid operated plunger for winding up the element upon energization, means for adjusting the stroke of the plunger, an energizing circuit including a normally closed contact and a normally open contact each of which is operated to its opposite 55 position immediately on energization of the solenoid, means for retaining the normally open contact in its closed position, and means for de-energizing the solenoid to cause a predetermined timed operation of the other contact 60 to closed position to thus close the circuit.

4. In combination, a clock-work timing element, a solenoid, a solenoid operated plunger for winding up the element upon energization, manual means for adjusting the stroke of the 65 plunger, an energizing circuit including a normally closed contact and a normally open contact each of which is operated to its opposite position immediately on energization of the solenoid, a holding coil for retaining the normally open contact in its closed position 70 less of the position of the plunger, means for automatically de-energizing the solenoid upon completion of its power stroke to cause a predetermined timed operation of the other contact 75 to a closed position to thus close the circuit.

5. In a time element relay, in combination, a casing, a solenoid including a core, a winding and a plunger and carried by the casing, a biased contact operable by the plunger, an armature carrying a contact and movable to operated position by the plunger, and a holding winding on said core, energized through the armature contact, for holding the armature in operated position when energized. 80

6. In a time element relay, in combination, a casing, a solenoid including a core, a winding and a plunger and carried by the casing, a biased contact operable by the plunger, an armature, a contact governed by the armature, an adjustable, lost motion operative connection between the plunger and the armature, the armature being movable to operated position by the plunger, and a holding winding on said core, and including the armature governed contact, for holding the armature in operated position 90 when energized. 95

7. In a time element relay, in combination, a casing, a solenoid including a core, a winding and a plunger and carried by the casing, a biased contact operable by the plunger, an armature, an adjustable, lost motion operative connection between the plunger and the armature, the armature being movable to operated position by the plunger, and a holding winding on said core for holding the armature in operated position 100 when energized, a timing element connected to be wound up when the plunger moves in one direction, and determine the rate of movement of the plunger in the opposite direction. 105

8. In a time element relay, in combination, a casing, a solenoid including a core, a winding and a plunger and carried by the casing, a biased contact operable by the plunger, an armature, an adjustable, lost motion operative connection between the plunger and the armature with the 110 armature movable to operated position by the plunger, a holding winding on said core for holding the armature in operated position when energized, and a circuit including the biased contact and a contact controlled by said armature, in series. 115

9. In a time element relay, in combination, a casing, a solenoid including a core, a winding and a plunger and carried by the casing, a biased contact operable by the plunger, an armature, an adjustable, lost motion operative connection between the plunger and the armature with the armature movable to operated position by the plunger, a holding winding on said core for holding the armature in operated 120 position when energized, a timing element connected to be wound up when the plunger moves in one direction, and determine the rate of movement of the plunger in the opposite direction, and a circuit including the biased contact 125 and a contact controlled by said armature, in series. 130

10. In a time element relay, in combination, a solenoid including a winding and a plunger, a biased contact operable by the plunger, an armature carrying a contact and controlled to operated position by the plunger, and a holding winding for holding the armature in operated position when energized through the armature contact. 140

11. In a time element relay, in combination, a solenoid including a winding and a plunger, a biased contact operable by the plunger, an armature, a contact controlled by the armature, an adjustable lost motion operative connection be- 145 150

- ween the plunger and the armature, the armature being movable to operated position by the plunger, and a holding winding for holding the armature in operated position when energized through the armature controlled contact.
12. In a time element relay, in combination, a solenoid including a winding and a plunger, a biased contact operable by the plunger, an armature, an adjustable, lost motion operative connection between the plunger and the armature, the armature being movable to operated position by the plunger, a holding winding for holding the armature in operated position when energized, a clock-work timing element connected to be wound up when the plunger moves in one direction, and determine the rate of movement of the plunger in the opposite direction.
13. In a time element, in combination, an operating member, electrical means for actuating the operating member, a contact operated by the operating member, an armature carrying a contact and movable to operated position by the operating member, and electric means depending upon the armature carried contact for holding the armature in operated position.
14. In a time element, in combination, an operating member, electrical means for actuating the operating member, a contact operated by the operating member, an armature controlling a contact and movable to operated position by the operating member and electric means energized through the armature controlled contact for holding the armature only when the armature is in operated position.
15. In a time element relay, in combination, a solenoid including a winding and a plunger, a biased contact operable by the plunger, an armature controlling a contact and controlled to operated position by the plunger and a holding winding for holding the armature in operated position when energized through the armature controlled contact.
